(57) **CLAIM**

The ornamental design for an automobile tire, as shown and described.

DESCRIPTION

FIG. 1 is a front view of the automobile tire, showing the new design, the top plan view and bottom plan view appearing the same as the front view;

FIG. 2 is a rear view of the automobile tire;

FIG. 3 is a right side view of the automobile tire;

FIG. 4 is a left side view of the automobile tire;

FIG. 5 is a fragmentary front view, showing in enlargement

the portion 5—5 in FIG. 1; and,

FIG. 6 is a sectional view, taken on line 6—6 of FIG. 5.

1 Claim, 5 Drawing Sheets

Matter enclosed in heavy brackets [] appears in the original patent, but forms no part of this reissue; matter printed in italics indicates the additions made by reissue.
